UNITED STATES PATENT OFFICE.

FRANK O. WILLEY, OF INDIANAPOLIS, INDIANA.

PERMUTATION LOCK FOR IGNITION SYSTEMS.

Application filed May 6, 1921. Serial No. 467,248.

To all whom it may concern:

Be it known that I, FRANK O. WILLEY, a citizen of the United States, and a resident of Indianapolis, in the county of Marion and State of Indiana, have invented new and Improved Permutation Locks for Ignition Systems, of which the following is a description.

The general object of the invention is to provide a novel device applicable to the coil box of a known type of automobile for locking the coil elements to prevent sur-
reptitious removal of the coils from the coil box.

15 A further important object of the invention is to provide an embodiment of the locking means referred to which will at the same time short-circuit the coil units.

The nature of the invention and its ad-
20 vantages and distinctive features will clearly appear as the description proceeds.

Reference is to be had to the accompanying drawings forming a part of this specification, it being understood that the drawings are merely illustrative of one example of the invention.

Figure 1 is a plan view of a locking case and permutation lock beneath the bottom thereof;

30 Figure 2 is a vertical section through the lock case on the line 2—2, Figure 1 and through the coil box, the view showing in edge view a latch element applicable to the respective coil units to be engaged or dis-
35 engaged by the lock bolts;

Figure 3 is a face view of the latch element;

Figure 4 is a plan view of one of the permutation disks;

40 Figure 5 is a plan view of a guide plate provided in the lock case for the latch bolt;

Figure 6 is a transverse vertical section on the line 6—6, Figure 1;

45 Figure 7 is a longitudinal vertical section on the line 7—7, Figure 1;

Figure 8 is a perspective view of the pivot stud for the permutation disks and functioning in the locking of the bolt.

In Figure 2 A indicates a coil box; a,
50 the cover thereof; B, a coil within the box here conventionally shown; C, the outer and lower coil terminals; D, the resilient contacts engageable with the terminals C; and E, the binding posts, for conductor wires.

55 The parts referred to are of known construction.

In carrying out my invention in the form illustrated I provide a lock case 10 adapted in practice to be positioned beneath the bottom of the coil box and secured thereto in any suitable manner to lie in a plane parallel with the bottom. A latch element 11 which in practice is made from flat metal is disposed vertically between a coil B and the back of the coil box and is formed with an eye 12 at its upper end to be slipped over the lower terminal C. The latch element 11 has a length to extend through a hole a' in the bottom of the coil box and project into the lock case 10 through the open top thereof. At the lower end the latch element 11 has a transverse hole 13 through which may be projected or from which may be withdrawn a latch tongue 15 formed on the end of the lock bolt 14, having a handle 16 at the front of the box A. The lock bolt 14 in the illustrated example is adapted for locking four coils and therefore consists of a long flat plate, the locking tongues 15 being formed integrally 80 therewith to project from the rear edge and spaced to lie in position for engagement with a plurality of elements 11.

On a centering stud 18 rising from the bottom of the lock case 10 near the front 85 a plurality of permutation disks 17 are placed to turn with the said stud as an axis. Extending radially from the eye or bore 17^a of each disk is a slot 19 and a slot 20 is formed transversely in the stud 90 18 so that when the slot of the stud and the three slots 19 of the disks 17 aline, the lock bolt 14 may be drawn outwardly to withdraw the latch members 15 from latch elements 11, thereby permitting the coils 95 with the latch elements 11 thereon to be lifted from the box A. With the bolt 14 shot forwardly to engage the elements 15 with the respective elements 11, the coils are locked by reason of the engagement of the elements 11 with the contact terminals C. For locking the bolt 14, it is formed with a depending flange 21 of a size to be accommodated in the slot 20 of centering stud 18 whereby the disks 17 may be freely turned about the 100 stud for throwing the respective slots 19 out of alinement to thereby prevent the flange 21 from moving out of the slot 20 of the stud.

In its sliding movements the bolt 14 is 110 guided at its inner end by a depending flange 22 thereon moving in a vertical slot

23 in a fixed upstanding member 24 of the lock case, said member 24 in the present example being struck up from a plate 25 secured in the case 10 at the bottom.

- 5 Each disk 17 is formed with annular indicating member 27, arranged in groups of ten separated by notches 28, for convenience in counting to a given point or in locating a given mark or symbol between or adjacent 10 to each member 27. There are ten groups of ten members each on each disk 17 and if three disks be employed as in the illustrated example, the assemblage permits of one hundred times one hundred different settings 15 or one million settings in all. For a zero point on the disk a tooth or radial protuberant member 26 may be utilized. In order to vary the relation of the members 27 to the position of the slot 19 in a disk 20 17, I form the outer or rim portion of the disk separate from the central portion 29, said rim portion and central portion being engaged by a corresponding toothed formation.

- 25 Normally, the bolt 14 is withdrawn in the outer position as presented by full lines in Figure 1 from which figure it will be observed that the locking flange 21 is partially in the slots 19 of the disks 17 and partially 30 in the slot of stud 18 in which position the latch members 15 are out of engagement with the latch elements 11. Upon the driver leaving the automobile, the handle 16 is pressed inwardly to move the bolt 14 and its 35 latch projections 15 rearwardly so that said latch projections engage the openings 13 in the respective elements 11. With the latching members 15 and bolt in engagement with the latches 11 the coils will be short-circuited since the elements 11 are hung upon the respective lower terminals C of the coils thereby cutting out the spark plugs.

I would state in conclusion that while the 45 illustrated example constitutes a practical embodiment of my invention, I do not limit myself strictly to the mechanical details herein illustrated, since manifestly the same can be considerably varied without departure from the spirit of the invention as defined in 50 the appended claims.

Having thus described my invention, I claim:

1. In a lock of the character described, a 55 slidable bolt, a series of permutation disks, a centering stud about which said disks may turn, the stud being slotted diametrically at one of its ends and the disks having each

a slot that may be brought into register with the stud slot, said bolt having a member accommodated in the slot and movable into the disk slots when the latter are in register with the stud slot, said bolt when said stud slot and said disk slots are alined being free to be slid in a plane transverse to the axis of the stud and to the axis of the disks. 60 65

2. In a locking means of the class described, a latch element having an opening at its lower end, a locking bolt formed with a projection adapted to engage or disengage said latch element, a series of permutation 70 disks having a central opening, a stud for said central opening about which said disks may turn, said stud presenting at its upper face a diametrically extending slot, said disks being each provided with a radially-extending slot which may be brought into register with the slot in the stud, and a member on said locking bolt normally accommodated in the stud slot and movable in the disk slots when the same are in register 75 with the stud slot whereby to permit a sliding of said bolt.

3. In a permutation lock of the class described, a plurality of superimposed disks, each having indicating means on their peripheries, an opening in the center and a radially-extending slot merging into said opening, a stud having a slot at one of its ends extending diametrically and pivoted to register with the slots of the disks, and a 80 bolt provided with a projection arranged within said slot in the stud and adapted to slide in the slots of the disks when the same are alined with the slot in the stud, said bolt being slidable in the plane of the disks 85 and transversely to the axis of said stud. 90 95

4. In a lock of the class described, a support, a stud having a diametrical slot in one of its ends arranged on stud support, a disk having an opening to receive said stud and a slot extending radially thereof adapted to register with said diametrical slot in the stud bolt slidable in the plane of the disk and crosswise of said stud passing above said disk, means integral with said bolt extending 100 within said slot in the stud, latch means, said bolt being formed at one end with projections normally engaging said latch means and dis-engageable therefrom when said slot in the disk is alined with the slot in the stud 105 and the bolt slid so as to cause said integral means to move from the slot in the stud into the slot in the disk.

FRANK O. WILLEY.
